Des. 226,820
Patented May 1, 1973

226,820

POST TOP COLONIAL LUMINAIRE

John B. Arens, Cleveland, Ohio, assignor to Westinghouse
Electric Corporation, Pittsburgh, Pa.

Filed Oct. 5, 1971, Ser. No. 186,595

Term of patent 14 years

Int. Cl. D26—03

U.S. Cl. D48—31

FIG.1

FIG.4

FIG. 1 is a side elevation view of a post top colonial luminaire embodying my new design;

FIG. 2 is a bottom plan view of the luminaire of my invention;

FIG. 3 is a top plan view of the luminaire of FIG. 1; and

FIG. 4 is a side elevation view of the luminaire of my invention taken at an angle of about 45° to the FIG. 1 view.

The supports for the luminaire shown in broken lines form no part of this invention and are for purposes of illustrating the environment only.

I claim:

The ornamental design for a post top colonial luminaire, substantially as shown and described.
